AUTOMATICALLY OPERATED SIGNALING APPARATUS

Raymond L. Freas, Conshohocken, Pa.

Application February 14, 1949, Serial No. 76,342

5 Claims. (Cl. 250—33)

(Granted under Title 35, U. S. Code (1952),
sec. 266)

1

This invention pertains to the art of signalling, and it comprises apparatus operable automatically to send out signals. More particularly, the device of the invention is adapted to be thrown to the earth from a moving vehicle. When it reaches the earth the device conditions itself automatically for transmitting signals, and thereafter the device operates automatically to transmit signals.

The present invention embodies certain improvements over the structure of my prior application, Serial No. 634,134, filed December 10, 1945, now abandoned, for a Radio Float, the subject matter of which is now pending in the continuing application, Serial No. 33,835, filed June 18, 1948, 15 Patent No. 2,593,432 granted April 22, 1952, entitled "Automatically Operated Signalling Apparatus."

The present invention embodies a novel extensible antenna construction, which constitutes 20 an improvement over the antenna disclosed in the hereinbefore referred to applications, Serial No. 634,134 of December 10, 1945, and Serial No. 33,835 of June 18, 1948. The improved antenna construction forms the subject matter of my 25 prior copending application, Serial No. 631,459, filed November 28, 1945, now abandoned, for an Automatically Erected Antenna, of which the present application is a continuation.

The present invention also embodies novel operating apparatus for erecting the antenna, which 30 is an improvement over the antenna erecting apparatus of the hereinbefore referred to applications, Serial No. 634,134 of December 10, 1945, and Serial No. 33,835 of June 18, 1948. The improved antenna erecting apparatus of the present application forms subject matter of my copending application, Serial No. 645,424, filed February 4, 1946, now abandoned, entitled "A Pressurized Floating Signalling Apparatus," of which 35 the present application is a continuation.

The novel characteristics and various advantages of the device of the present invention will be understood from the accompanying drawing. In the drawing:

Fig. 1 is a cross-sectional elevation through the longitudinal center plane of the apparatus of the invention, certain parts appearing in elevation, and with parts broken for clearness of illustration;

Fig. 2 is a fragmentary cross-sectional elevation, showing a detail of the buoyancy chamber;

Fig. 3 is a fragmentary cross-sectional elevation, illustrating the antenna in erected condition;

2

Fig. 4 is cross-section taken on line 4—4 of Fig. 3;

Fig. 5 is a perspective in cross-section, illustrating one form of pressure-sealing piston embodied in the antenna, and

Fig. 6 is a similar perspective in cross-section illustrating another form of pressure-sealing piston embodied in the antenna.

The device of the present invention embodies a signal-transmitting radio. When the device is thrown from a moving vehicle, from an airplane in flight, for example, it operates automatically to condition itself to set the radio in operation, and thereafter the radio operates automatically to send out signals. The invention is particularly useful during a flight over a large body of water when the pilot desires to check direction to determine the amount of drift; the disclosed embodiment, therefore, being particularly constructed to operate automatically when it is thrown into water. The invention of the present application is similar to, and an improvement over, the device of my copending application, Serial No. 33,835, hereinbefore referred to.

The apparatus disclosed comprises a tube 11, which contains and houses the antenna 12 when it is in collapsed condition. The tube 11 is preferably of fiber, plastic impregnated fabric or other suitable dielectric material.

The tube 11 provides a foundation or base that supports the radio attached thereto. The heavier components 15 of the radio, in general constituting the power pack, are attached to the tube 11 at one of its ends to provide a weight or ballast mass.

The end sleeve 16 fits into the cavity 14 of the nipple 17 of bracket 18 and is screw-threaded onto the end of tube 11. The reinforcing sleeve 19 supports the tube 11 and adds rigidity for a portion of its length extending away from the end attachment onto bracket 18. Sleeves 16 and 19 are provided with shoulders 20, as shown, which are clamped together and into engagement with the end face of nipple 17 by the nut 21 being screwed onto the nipple 17, suitable gaskets 22 being provided to make the attachment watertight. The power pack 15 is mounted in any suitable manner on plate 23, which is secured to the bracket 18 by means of one or more bolts 24 and by other means to be described hereinafter.

At its end remote from the bracket 18, the tube 11 is attached to the buoyancy chamber 25 by means of the sleeve 26. The buoyancy chamber is an elongated can 27 having a lid 28 that forms one end of the chamber 25. The end

of the chamber opposite the lid 28, i. e., the bottom of the can 27, is provided with a fitting 29 for attachment of the buoyancy chamber 25 to the sleeve 26. The buoyancy chamber 25 is thus fastened to the tube 11 positioned around it, and it extends from the end attachment of fitting 29 and sleeve 26 lengthwise of the tube towards the bracket 18.

The source of electricity for the radio signalling apparatus is the battery 30 which is the type that is inert but becomes activated by contact with water. When it is desired to put the apparatus in operation to send out signals while the launching craft is flying over a body of water, the battery 30 becomes energized by the apparatus being thrown into the water. This eliminates the need of electrical switches. Upon the battery becoming energized, it first supplies energy to the apparatus which operates to erect the antenna in a manner to be described more fully hereinafter. The battery thereafter continues as an electrical supply for the radio transmitter for sending out signals.

The battery 30 is constructed with the central aperture or hole 31 through which the tube 11 extends from the buoyancy chamber 25 to the end attachment thereof with bracket 18, the battery being thus positioned between the buoyancy chamber and the power pack 15. The battery 30 is attached to the bracket 18 and constitutes part of the ballast mass provided by the power pack 15. The hole 31 fits loosely around the tube 11 as shown, and has sufficient clearance for certain lines to extend through it that will be described more fully hereinafter. Posts 32 and 33 are attached to the end of battery 30, and serve to secure the battery to the bracket 18 by means of the respective bolts 24 and screw 34. Steadying bracket 35 is secured to the end of battery 30 and fits snugly around the exterior surface of reinforcing sleeve 19 thereby to make the attachment of battery 30 to the tube 11 more rigid.

In accordance with the described construction, the buoyancy chamber 25 and the battery 30 constitute an elongated structure of generally cylindrical contour, with the power pack 15 attached to one end thereof, and the tube 11 provides a concentrically located central frame that supports the various components of the apparatus.

For attaching the buoyancy chamber 25 to one end of tube 11, the sleeve 26 is screw-threaded to the end of the tube 11 remote from the bracket 18 and is extended through the fitting 29 of the buoyancy chamber 25. The inside nut 40 is screw-threaded onto the sleeve 26 and is brought into engagement with the fitting 29 on the inside of the can 27. The outside nut 41 is also threaded onto sleeve 26, and is tightened into the fitting 29 opposed to the inside nut 40, suitable gaskets 42 being provided to make the attachment watertight. The water seal or packing nut 45, including suitable gaskets 46, are provided to make the attachment watertight along the screw threads between the sleeve 26 and the nuts 40 and 41. By means of the described construction, the end of tube 11 remote from bracket 18 and the buoyancy chamber 25 are rigidly secured to each other at the outboard end of the chamber 25.

The buoyancy chamber 25 is secured to the tube 11 at its end remote from the fitting 29 for greater rigidity. The lid 28 is provided with the fitting 44 through which the tube 11 extends, and the nut 47 is tightened into the fitting 44 to make the attachment rigid, suitable gasket 48 being provided to make the connection watertight.

The antenna 12 in collapsed condition is housed in the tube 11 and is adapted to be erected by being extended out of the outboard end of the tube 11 that embodies the sleeve 26. In its collapsed condition, the antenna is enclosed in the tube 11 by means of the disc 50 of blotting paper or the like material that disintegrates and loses its strength when it is placed in contact with water. The disc 50 is held clamped against the end surface of the sleeve 26 by means of the end collar 51, and is reinforced by the disc 52 of metal or the like material to which it is attached by means of the central rivet 53. The metal disc 52 fits loosely in the bore of the collar 51 and is positioned therein until the antenna 12 is erected. The metal disc 52 has a larger diameter than the bore of the sleeve 26 and thus prevents collapse of the blotter disc 50 in the event it is hit during normal handling of the device of the invention.

The lighter-weight components of the signalling apparatus are preferably housed in the buoyancy chamber 25, and these in general constitute the transmitting components of the radio. The transmitting components are generally larger than components of the power pack and are less rugged, and they are protected against injury by being housed in the buoyancy chamber. The cable 55 connects the components that are housed in the buoyancy chamber 25 with the power pack 15, and extends from the power pack through the hole 31 of battery 30 to the lid 28 of the buoyancy chamber. The cable 55 enters the buoyancy chamber 25 through the watertight grommet 56 of rubber or the like suitable material, which is attached to the lid 28 in any suitable manner as shown.

The structure described so far is similar to the disclosure of the copending application, Serial No. 33,835, and is adapted to be operated in the same manner. Accordingly, the complete device includes a parachute, which is constructed and attached to the ballast mass 15 in the same manner as in the copending application, and requires no further description herein.

Any suitable radio transmitter can be employed having any suitable circuit. For example, the circuit can be the same as is disclosed in the copending application. In the embodiment of the present application, capacity tuning is disclosed, and is available alternatively with the inductance tuning of the copending disclosure.

The fixed plate 57 is clamped to the sleeve 26 by means of nut 58, and is electrically connected to the transmitting component housed in the chamber 25 by means of lead 59. The movable plate 60 is threaded into the fitting 61, which extends through the wall of the chamber 25 and is suitably located to enable the plate 60 to be adjustably positioned towards or away from the fixed plate 57 for tuning, the adjustment being made from the exterior of the chamber 25. The fitting 61 is attached to the can 27 in a fluidtight manner by brazing, soldering or the like, and the cap 62 is provided to close the fitting and render it completely watertight and airtight in use.

The buoyancy chamber 25 of the present application differs from the buoyancy chamber in the copending application, Serial No. 33,835, in that chamber 25 is pressure tight. In the earlier construction of the copending application, the buoyancy chamber is under atmospheric pressure, and air passages are provided that permit air to pass out of and into the chamber to and from the exterior atmosphere. The lid 28 of chamber 25

is sealed to the can 27 at 63, by soldering, brazing or the like, and provision is made to place the chamber 25 under fluid pressure.

The valve 65, Fig. 2, is provided, to enable air or other suitable fluid under pressure to be fed into the buoyancy chamber 25. The operating mechanism of the valve 65 of the disclosed embodiment is the same in all particulars as the type of air valve that is conventional and well-known in automotive tires. It is therefore not deemed necessary herein to describe the structure of valve 65 in detail. In actual reduction of the invention to practice, applicant provided the fitting 66 in the bottom end of can 27, the fitting 66 being adapted to accommodate a conventional automotive tire valve, and this construction has proven entirely satisfactory. In practice, the buoyancy chamber 25 is preferably placed under pressure of about one atmosphere, but the pressure can be varied within wide limits to suit particular needs.

The chamber 25 may be provided with other fittings, such as the fitting 67, for example, which permits access to the interior of the chamber for particular purposes that are unimportant for understanding the present invention.

Bracket 18 includes the enclosure of cavity 70, to which the buoyancy chamber 25 is connected by means of the tubing or duct 71. The lid 28 is provided with the fitting 72 to which one end of the duct 71 is attached by soldering or the like. The other end of duct 71 is similarly attached to fitting 73 of the bracket 18 and thereby communicates with the cavity 70. The duct 71 preferably passes from the buoyancy chamber 25 to the fitting 73 through the hole 31 in battery 30.

The cavity 70 is closed at its end remote from the fitting 73 by the diaphragm 75 of sectile material which, in the disclosed embodiment, comprises a disc of thin sheet metal. The diaphragm 75 is held in place by means of the fitting 76, suitable gaskets being provided to seal the cavity 70 fluidtight.

The bracket 18 embodies the nipple 77, which is threaded exteriorly to receive the nut 78. This serves as an attachment of the plate 23 to the bracket 18 in addition to the bolt 24 previously described.

The nipple 77 provides an enclosure or cavity 79, which is connected with the cavity 70 through the bore or duct 80 of the fitting 76. The diaphragm 75 constitutes a wall or partition that prevents communication between the cavities 70 and 79.

The cavity 14 of nipple 17 communicates with the interior of tube 11 through the tubing 81 that is fastened in the bore of, and forms a lining for, the end sleeve 16 of the tube 11. The cavity 14 of nipple 17 communicates with the cavity 79 of nipple 77 through the duct 82, whereby the cavity 79 is in constant communication with the tube 11.

Mechanism, generally designated 85, is operable to pierce the diaphragm 75 and open a passage through it, thereby operating to connect the cavities 70 and 79 and connect the buoyancy chamber 25 with the antenna housing tube 11 for fluid flow thereto. The cap 86 is threaded exteriorly of nipple 77, and comprises the axial bore 87 that embodies a combustion chamber. A suitable explosive 88 is confined in a predetermined space within the chamber 87 by one or more partitions 89 of celluloid or the like combustible material. The firing device 90 is threaded into the bore of cavity 87, and confines the combustion

chamber. The firing device 90 is an electrical heating unit, and comprises the resistance coil 91, which is fed through the lead 92 from battery 30 as a source of electricity. The heating unit is provided by reconstructing an automotive spark plug, this being done by connecting the resistance wire 91 across the spark gap. The cap 93 houses the firing device 90 as shown, and includes the eye 94, to which a parachute is attached in the manner disclosed in copending application Serial No. 33,835.

The bore of cavity 79 serves the purpose of a cylinder in which the plunger or piston 95 operates. The pin 96 is attached to the plunger 95, and extends into the bore 80 of the fitting 76 in which pin 96 is guided during travel of the plunger 95. The compression spring 97 acts against the plunger 95 and urges it into abutment with the cap 86. The pin 96 is pointed at its end 98 for piercing the diaphragm 75, and ducts 99 extend through the pin 96 from its end 98 embodying the point to the cavity 79. Thus, fluid under pressure is enabled to flow from cavity 70 into cavity 79 when the diaphragm 75 is pierced by the point 98 of pin 96.

Operation of the device will now be described with reference to the disclosed embodiment, which is particularly adapted to be thrown to the earth from an aircraft in flight over a body of water. When the apparatus is launched, it descends to the earth hanging from a parachute in the manner described fully in the copending application Serial No. 33,835. The sleeve 26 at the outboard end of the tube 11 is directed downwardly during the descent, and therefore the disc 50 of blotting paper is first submerged in the water and begins to disintegrate and lose its strength.

When the device becomes deposited on the body of water, the ballast mass 15, including battery 30, sinks and the buoyancy chamber 25 floats on the surface. The sleeve 26 thereby comes to the top, and the bottom of can 27 with the end collar 51 of sleeve 26 projects above the surface of water. The battery 30 being under water, it thereby becomes energized. Electricity is supplied to the firing device 90 from the battery 30, causing the heating coil 91 to become heated. When the temperature of coil 91 becomes high enough to detonate the explosive 88, combustion takes place in the chamber 87, and pressure of gas expansion is generated that actuates the plunger 95 in opposition to the spring 97. The point 98 of the pin 96 is thereby driven through the diaphragm 75.

This releases the fluid under pressure contained within the buoyancy chamber 25, and permits it to flow into tube 11, passing through the ducts 99 of pin 96 into cavity 79, and to the interior of the tube 11 through duct 82, the cavity 14 of nipple 17, and the lining tubing 81 of the end sleeve 16 of tube 11.

The pressure fluid supplied to the tube 11 by the buoyancy chamber 25 is not excessively violent. Combustion of the explosive 88 operates under much greater pressure, but the operating pressure of the explosive continues for a much shorter length of time. The operating characteristics of an explosive may vary and are not predictable precisely. With the device of the present invention, operation of the explosion is quick, and invariably sufficiently forceful to drive the pointed end 98 of pin 96 through diaphragm 75. The pressure fluid from the buoyancy chamber 25 operates with a steady and persistent force.

The volume of the buoyancy chamber is great enough to prevent appreciable pressure loss due to volumetric displacement of the antenna.

The disc 50 of blotting paper having lost its strength by having been submerged, the release of the pressure fluid from buoyancy chamber 25 into the tube 11 operates to push the antenna 12 out of the end of sleeve 26, and it shears the disc 50 without encountering appreciable resistance. The pressure fluid exerts a steady force with continuing uniform magnitude, which operates to erect antenna 12, and as the apparatus rolls and bobs on the surface of the water this operates to agitate the antenna 12 within the tube 11 to thereby assist in the operation of erecting the antenna.

The antenna comprises the outer tube 101 that fits loosely inside the housing tube 11, and the successively smaller tubes 102, 103 and 104 that fit loosely, one inside the other. The tubes 101, 102, 103 and 104 are approximately of equal length, and are nested each inside the next larger tube in the manner illustrated in Fig. 1. Between the smallest and largest tubes, 104 and 101 respectively, there are as many intermediate-sized tubes as are required to provide the required total length of antenna 12. The tubes of antenna 12 are constructed of any suitable metal, aluminum tubing having been employed in the disclosed embodiment with results that are entirely satisfactory.

The rims of opposite ends of each of the antenna tubes 101, 102, 103 and 104 are rolled, the inboard end of each tube being spun outwardly to embody the outwardly directed bead 105 and the outboard end of each tube being spun inwardly to embody the inwardly directed bead 106. Each smaller tube 104, 103 and 102 is thereby adapted to be inserted into the inboard end of its next larger tube 103, 102 and 101 respectively, and to be projected through its next larger tube until the trailing or inboard end of the smaller tube reaches the outboard end of its next larger tube. The respectively outwardly and inwardly directed beads 105 and 106 overhang each other, and are accordingly disposed in opposed relationship when the inboard end of each smaller tube approaches the outboard end of its next larger tube. This prevents any smaller tube from being projected through and out of its next larger tube, and operates to hold the several tubes attached to each other end to end when the antenna 12 is in erected condition.

As illustrated in Fig. 3, each of the smaller tubes 102, 103 and 104 is provided with a spring contact 107 of bronze or the like electrically conducting material. Each spring contact 107 is attached to its tube 102, 103 or 104 near the inboard end thereof, and extends along the tube into a position proximate to the outwardly directed bead 105. The spring contact 107 is attached to and held in electrical contacting engagement with the outside surface of its tube 104, 103 or 102 by means of a wrapping of adhesive tape 108 that overhangs the inwardly directed bead 106 of the next larger tube 103, 102 and 101 respectively. The spring 107 presses resiliently against the inside surface of the next larger tube, thereby maintaining electrical contact between tubes throughout the distance of their relative movement. When the antenna is erected by the smaller tubes 104, 103 and 102 being actuated in an outboard direction through their respective next larger tubes 103, 102 and 101, the wrappings 108 are driven into engage-

ment with the beads 106, and being yielding they permit movement of the springs 107 that causes them to jam between their outwardly turned beads 105 and the inside surface of the respective next larger tube 103, 102 or 101.

Near its inboard end, each smaller tube 104, 103, 102 is provided with a radial enlargement 109 located at a distance from the end of the tube to position it just beyond the beaded end 106 of the next larger tube 103, 102, 101 respectively, when the antenna 12 is in fully erected condition. One or more properly circumferentially positioned pimples provide a satisfactory radial enlargement 109, and serve as an additional means to inhibit collapse of the antenna after it has been extended to its erected condition.

The largest tube 101 is provided with a resilient connector 110 near its inboard end, which holds the antenna 12 mechanically in erected condition and also serves as an antenna coupling.

As seen in Fig. 3, the sleeve 26 has a main bore 115 approximately the same size as the bore of the tube 11. On its end that is threaded to the tube 11, sleeve 26 is provided with a counterbore 116 of somewhat larger diameter than the main bore 115, the counterbore 116 forming an annular recess in association with the end of tube 11. The resilient connector 110 of the tube 101 engages the annular recess 116 to hold the antenna 12 in erected position. Near its inboard end, the largest tube 101 of the antenna is provided with a diametrically disposed aperture in which the plungers 118 are guided for movement radially. Spring 117 operates to press the plungers 118 radially outwardly against the inside wall of the tube 11 when the antenna is in collapsed condition of Fig. 1, the antenna circuit being then open because of the dielectric properties of tube 11. During movement of tube 101 out of the end of the tube 11 that includes the sleeve 26, when the plungers 118 reach the end of the tube 11 they are actuated into the recess 116 by the spring 117. The plungers 118 constitute latching means that holds the antenna mechanically in erected position. Plungers 118 also make electrical contact between the tube 101 and sleeve 26, thereby coupling the antenna 12 electrically with the fixed plate 51 of the radio transmitter.

A metal bushing 119, Figs. 3 and 4, of bronze or the like friction resisting material, provides a bearing guideway for the plungers 118. The rubber mount 120 contains the bushing 119, and is pressed inside the tube 11 in position to locate and hold the latch 117, 118 of the holding device 110 in position. The rubber mount 120 is provided with ports 121, the function of which will be made clear hereinafter.

At its inboard end, each tube 104, 103, 102 and 101 is provided with yielding piston 125, 126, 127, 128, respectively, of rubber or the like resilient material.

The piston 125 for the smallest tube 104 is illustrated in detail in Fig. 6, and comprises a base 129 in the form of a plug which fits into the inboard end of tube 104. The truncated apron 130 extends away from the annular shoulder 131 that borders the base 129. With the shoulder 131 abutting against the bead 105 of tube 104, the apron 130 extends beyond the end of the tube, and bears resiliently against the inside surface of the next larger tube 103. Fluid under pressure acts against the inside of apron 130 to

press it against the inside surface of the next larger tube 103, and seals the tubes against leakage of pressure fluid. The plug 129 of piston 125 is solid, and closes the tube 104 against pressure fluid entering it. The inside tube 104 is thereby sealed off and is not involved in the volumetric displacement of the antenna 12 being erected.

The piston 126, Fig. 5, comprises the base 133 which is plugged into the inboard end of tube 103, with the shoulder 134 abutting against the beaded end 105 of the tube. Resilient apron 135 extends beyond the inboard end of tube 103, and it bears against the inside surface of the next larger tube 102, functioning in a manner similar to piston 125. The base 133 of piston 126 is provided with an axial aperture 136 that permits fluid under pressure to enter the smaller tube 103 from the larger tubes 102, 101 and 11.

The pistons 121 and 123 of tubes 102 and 101 respectively, are constructed similar to the piston 126, Fig. 5, and bear against the inside surface of respective next larger tubes 102 and 11, functioning in a similar manner. The several pistons 128, 127 and 126 differ in size only, to fit their respective tubes.

By means of this construction, the pressure fluid from the buoyancy chamber 25 that enters tube 11 passes through the axial aperture 138, Fig. 3, of piston 128, which communicates through the ports 121 of the rubber mount 120 to permit pressure fluid to enter tube 101. The pressure fluid enters tube 102 through piston 127, and enters tube 103 through the aperture 136 of piston 126. The pressure fluid acts against the closed plug 125 of tube 104 to project tube 104 lengthwise out of the outboard end 106 of tube 103. Tubes 103, 102 and 101 are pushed out of the outboard ends of respective tubes 102, 101 and 11 in a similar manner by operation of pressure fluid in tube 103 against the closed piston 125. This action continues until the several tubes 104, 103, 102 and 101 reach the limits of their movements in the outboard direction, when the respective outwardly and inwardly directed beads 105 and 106 of next adjacent tubes oppose each other, in each instance with a spring 107 between them. When the latching plungers 118 move into the annular recess 116 of sleeve 26, the antenna 12 is then in erected condition, and is coupled to the radio transmitter.

At its outboard end, the smallest tube 104 is provided with a button 122 of rubber or the like material, which serves as a buffer that operates against the blotter disc 50 to push the discs 50 and 52 out of the collar 51 and out of the way when the antenna 12 is erected. The button 122 overhangs the outside diameter of the smallest tube 104, and also overhangs the end of the next larger tube 103, to thereby hold the tube 104 located in the inboard direction within the tube 103 when the antenna is positioned in collapsed condition. This prevents the piston 125 from being held in crushed condition against the piston 126 of tube 103. See Fig. 1.

For a similar purpose, each successively larger tube 103 and 102 is provided with an external band 123, 124, respectively, of rubber or the like material, which overhangs the beaded end 106 of its respective next larger tube 102, 101, and holds the tubes located in the inboard direction to prevent their pistons 126 and 127 from being held crushed against their respectively adjacent piston 127 and rubber mount 120 of tubes 102 and 101 respectively.

The lining tubing 81 of the end sleeve 16 of tube 11 abuts against the shoulder 139 of piston 128 interiorly of its apron and provides a stop that limits movement of the antenna 12 in the inboard direction of the tube 11, and serves to locate the antenna in collapsed condition housed within the tube 11. The tubing 81 prevents the apron of piston 128 from being held in crushed condition when the antenna 12 is in collapsed condition. See Fig. 1.

The disclosed structure is one practical embodiment of the invention, and does not limit its scope, which is determined by the accompanying claims.

The invention described herein may be manufactured and used by or for the Government of the United States of America for governmental purposes without the payment of any royalties thereon or therefor.

I claim:

1. In signalling apparatus adapted to operate from the surface of a body of water, a buoyancy chamber containing fluid under pressure, an antenna extensible by the operation of fluid under pressure, a housing tube containing the antenna in collapsed condition, a fluid passage from the buoyancy chamber to the tube, the fluid passage being normally in closed condition, and mechanism operable by the apparatus being deposited in water to open the fluid passage.

2. In signalling apparatus adapted to operate from the surface of a body of water, a buoyancy chamber containing fluid under pressure, an antenna extensible by the operation of fluid under pressure, a tube containing the antenna in collapsed condition, a fluid passage from the buoyancy chamber to the tube, a diaphragm sealing the fluid passage, and mechanism operable by the apparatus being deposited in water to pierce the diaphragm for fluid flow therethrough.

3. An extensible antenna comprising a plurality of metallic tubes containing one another telescopically, each tube comprising an outwardly-turned bead integral with the tube at its one end, each larger tube comprising an inwardly-turned bead integral with the tube at its other end that overhangs the outwardly-turned bead of the next smaller tube, a housing tube of conductor material containing the antenna in collapsed condition, a contact spring attached to each smaller tube near its end adjacent the outwardly-turned bead and bearing resiliently against the inside surface of the next larger tube in electrical contacting engagement therewith, an adhesive tape wrapped around each contact spring and its tube to attach the spring to the tube and hold it in electrical contacting engagement therewith, the adhesive tape wrapping extending away from the surface of its tube far enough to overhang the inwardly-turned bead of the next larger tube.

4. An extensible antenna comprising a plurality of metallic tubes containing one another telescopically, each tube comprising an outwardly-turned bead integral with the tube at its one end, each larger tube comprising an inwardly-turned bead integral with the tube at its other end that overhangs the outwardly-turned bead of the next smaller tube, a housing tube of conductor material containing the antenna in collapsed condition, a contact spring attached to each smaller tube near its end adjacent the outwardly-turned bead and bearing resiliently against the inside surface of the next larger tube in electrical contacting engagement therewith,

the housing tube being open at the end thereof remote from the pistons of the antenna tubes, an internal annular recess in the housing tube near the open end thereof, an electrical contact spring-pressed radially outwardly of the largest antenna tube into engagement with the inside surface of the housing tube, and positioned to lodge in the annular recess when the antenna is erected.

5. In signalling apparatus that is normally inoperative, a chamber containing fluid under pressure, an antenna extensible by operation of fluid under pressure, an electrical signal sending instrument and an electrical power source therefore, and mechanism operable by the electrical power source when it energizes the signal sending instrument to connect the chamber with the antenna for fluid flow thereto.

RAYMOND L. FREAS.
